UNITED STATES PATENT OFFICE.

VITTORIO PASTRENGO, OF SAN FRANCISCO, CALIFORNIA.

WINDOW.

Application filed December 10, 1924. Serial No. 755,003.

My invention relates to improvements in windows wherein a window pane is mounted within an inner sash portion which is pivotally and slidably movable with respect to an outer sash portion which in turn is counterbalanced for sliding movement within a casement.

The primary object of my invention is to provide an improved window adapted to be moved pivotally to an open position independently of the position of a sliding sash therefor within a casement.

Another object is to provide an improved device of the character described wherein the pane is pivotally and slidably movable with respect to the sash to permit said pane to be substantially reversed within said sash.

Another object is to provide an improved window provided with improved counterbalancing means adapted to facilitate the movement of the sash within the casement and to hold the sash in closed or adjusted position.

Another object is to provide an improved sash having a pivotally movable inner sash portion with improved means movable to engage and hold said inner portion in any of a plurality of open positions independently of the position of the sash proper.

I accomplish these and other objects by means of the device disclosed in the drawings forming a part of the present specification wherein like characters of reference are used to designate similar parts throughout said specification and drawings and in which—

Fig. 1 is a front elevation of my improved window, portions being broken away and shown in section to disclose the manner in which the sashes are mounted and counterbalanced within a casement.

Fig. 2 is a vertical section through a casement showing the manner in which the sashes are counterbalanced.

Fig. 3 is a vertical section through the casement and sash, showing the manner in which the inner sash portions are pivotally moved and held in open position.

Fig. 4 is a vertical section similar to Fig. 3, showing the inner sash portions in their reversed positions within the outer sash portions.

Fig. 5 is an enlarged sectional detail taken upon the line 5—5 of Fig. 1 in the direction indicated.

Fig. 6 is an enlarged sectional detail taken upon the line 6—6 of Fig. 2 in the direction indicated.

Referring to the drawings, the numeral 1 is used to designate in general a window casement within which is mounted a pair of window sashes each consisting of an outer sash portion 2 and an inner sash portion 3 pivotally mounted within said outer portion by means of pivot mountings 4 secured upon said outer portion 2 and engaging a longitudinally disposed slot 6 formed in the adjacent edges of the inner sash portion 3.

Transparent panes of glass 7 are mounted within the inner sash portions 3 in the ordinary manner, said inner sash portions being fitted closely into the frame formed by the outer sash portion 2 and matching therewith whereby said inner and outer sash portions combine to operate in the manner of the ordinary window sash for sliding movement within the casement.

Racks 8 are secured upon the sides of the outer sash portions 2 along the entire length thereof, said racks being engaged by gears 9 rotatably mounted within the casement 1 upon shafts 11. The gears 9 extend into meshing relation with the racks 8 through openings 12 formed in facings 13 constituting the sides of the casement whereby movement of the sashes within the casement will rotate the gears 9. Sprockets 14 are mounted upon the shafts 11 in connection with each gear 9 for rotation therewith. Chains 16 are mounted over the sprockets 14 said chains being adapted to be moved by said sprockets to raise and lower counterweights 17 suspended upon one end of each chain 16. The counterweights operate through the chains and sprockets to counterbalance the weight of the sashes supported by means of the racks 8 upon the gears 9 thereby facilitating the raising and lowering of the sashes within the casement and normally holding the sashes in any desired position with respect to the casement.

The pivot mountings 4 by which the inner sash portions 3 are supported within the outer sash portions 2 consist preferably of rollers mounted upon the ends of pins 18 extending through the sides of the outer sash portion and provided with flanged heads 19 inset into the side of the sash and held in position by the racks 8. The rollers normally engage the extreme upper ends of

the slots 6 and are arranged at a point considerably above the center of the sash whereby the inner sash portion may be swung pivotally to open position and re-
5 turned to normal closed position.

Props 21 are pivotally mounted within the inner sides of the outer sash portions 2, said props being normally enclosed within recesses 22 whereby the inner sash portion 3 may be moved to closed position. Sufficient sliding movement is afforded the props within their mountings to permit the entire prop to be moved outwardly from the recess and swung to engage the inner sash portion 3 when moved to a partially opened position whereby said sash may be held in any one of a plurality of positions. The inclination at which the inner sash portion 3 is held varies with the inclination at which the 20 prop is placed to engage the sash.

In operation, the sashes are mounted for sliding movement between the facing 13, said sashes being guided by guide strips 23 in the ordinary movement. The chains 16 and counterweights 17 are so arranged that when the upper sash is lowered the weight connected therewith will be raised from the lowermost portion of the casement an amount equal to the movement of the sash. 25 The weight connected to the lower sash is arranged to be lowered as the lower sash is raised, as best illustrated in Fig. 2 of the drawings, the position of the sash and weight in a partially raised position being 30 shown in dotted lines.

The inner sash portion 3 normally matches with the outer sash portion 2 and is moved therewith. When it is desired to open the window pivotally with respect to the sash, 40 the inner sash portion is moved outwardly at its bottom, said inner sash swinging about its pivot mounting 4 to the desired position. As the inner sash portion is moved outwardly, the props 21 are exposed 45 and may be moved outwardly to engage and support the inner sash portion in open position as shown in Fig. 2 of the drawings. The outward pivotal movement of the inner sash portion does not effect the sliding move- 50 ment of the outer sash section 2 which may

be raised and lowered in normal manner as indicated in dotted lines in Fig. 3 the lower sash being shown in vertically raised and outwardly swung position.

The slots 6 are made sufficiently long to 55 permit the inner sash portion to be substantially reversed within the outer sash portion. When the inner sash portion is moved to a partially opened position the slots 6 permit a sliding movement of said sash portion 60 along the pivot mountings whereby the bearings 4 may be caused to engage the opposite end of the slots 6 and the sash portion moved to reversed position as shown in Fig. 4 of the drawings. This provision permits 65 the window to be reversed and both sides washed from the interior of a room.

Having thus described my invention what I claim as new and desire to secure by Letters Patent is,

1. A counterbalancing means for window sashes comprising racks mounted upon the outer sides of upper and lower sashes slidably mounted within a casement; gears mounted within the casement in meshing 75 relation with the racks; sprockets mounted in connection with the gears; chains mounted over said sprockets, said chains having their ends hanging freely within the casement; and counterweights mounted upon 80 one end of each chain to counterbalance the sashes within the casement.

2. A counterbalancing means for window sashes comprising racks mounted upon the outer sides of upper and lower sashes slidably mounted within a casement; shafts mounted within the casement upon opposite sides of the sashes opposite the adjacent edges of said sashes; gears mounted upon 90 said shafts in meshing relation with the racks, said chains having their ends hanging freely within the casement, sprockets mounted in connection with each gear and rotatable therewith; chains mounted over the sprockets; and counterweights mounted upon 95 one end of each chain to counterbalance the sashes within the casement.

In witness whereof I hereunto set my signature.

VITTORIO PASTRENGO.
